UNITED STATES PATENT OFFICE.

EARL T. STRONG, OF URBANA, ILLINOIS, ASSIGNOR OF ONE-THIRD TO JAMES A. GIBSON AND ONE-THIRD TO EDWARD J. BUCKBEE, BOTH OF URBANA, ILLINOIS.

STAY-BOLT CUTTER.

No. 852,302.

Specification of Letters Patent.

Patented April 30, 1907.

Application filed December 28, 1905. Serial No. 293,654.

To all whom it may concern:

Be it known that I, EARL T. STRONG, a citizen of the United States, and a resident of Urbana, in the county of Champaign and 5 State of Illinois, have invented a new and Improved Stay-Bolt Cutter, of which the following is a full, clear, and exact description.

The invention relates to boilermaker's implements, and its object is to provide a 10 new and improved stay bolt cutter arranged to permit of conveniently and quickly cutting the stay bolt inside of the sheet, to facilitate removal of a worn-out fire-box of a locomotive or other boiler, and without first requiring the removal of the back sheet of the boiler.

The invention consists of novel features and parts and combinations of the same, which will be more fully described herein- 15 after and then pointed out in the claim.

A practical embodiment of the invention is represented in the accompanying drawings forming a part of this specification, in which similar characters of reference indicate corresponding parts in all the views.

Figure 1 is a side elevation of the improvement as applied, the stay bolt and boiler sheet being shown in section; Fig. 2 is a longitudinal sectional elevation of the same, 20 showing the cutter in an inactive position; Fig. 3 is a rear end view of the improvement; Fig. 4 is a front end view of the same; Fig. 5 is a plan view of the same, the rotating or driving sleeve being shown in section; Fig. 6 is a sectional plan view of the forward end of the improvement, on the line 6-6 of Fig. 2; Fig. 7 is a transverse section of the improvement, on the line 7-7 of Fig. 2; Fig. 8 is a 25 perspective view of the lever for carrying the cutter; and Fig. 9 is a like view of the cutter.

On the cylindrical stock A of the implement is mounted to slide lengthwise a sleeve B, provided, at its outer end, with keyways B' adapted to be engaged by a key held on the driving shaft C of a suitable motor employed for rotating the sleeve B, and with it the stock A, as hereinafter more fully described, the said shaft C being held in position on the sleeve B by a nut D, as indicated in the drawings. The sliding movement of the sleeve B on the stock A is limited by a stop-plate E fastened to the outer end of the stock A by screws E', and the said stop-

plate E is adapted to abut against an annular shoulder B² formed on the forward end of the sleeve B, as plainly indicated in Figs. 2 and 5.

The stock A is provided with a lengthwise-extending slot A' in which extends a lever F, 60 carrying, at its forward end, a cutting tool G and fulcrumed on a pin H secured in the stock A. The cutting tool G is provided with a radially-extending cutting edge G', adapted to cut the tubular end of the stay bolt I a 65 distance inside of the boiler-sheet I', as plainly illustrated in Figs. 1 and 2. The forward end A² of the stock A is reduced and preferably made of a separate piece, secured by pins A³ to the forward end of the stock A, 70 and the said reduced end A² is adapted to pass into a drill hole I² formed in the outer end of the stay bolt I. The slot A' is continued into the removable end A², but terminates a distance from the outer terminal 75 thereof, and in this terminal is formed a chip-receiving recess A⁴ to allow accumulation of chips cut by the cutting edge G' until the implement is removed from the stay bolt 80 after the same is cut in two.

The cutting tool G is preferably removably held in the forked end F' of the lever F, to permit interchange of cutting tools in case one is worn out, each cutting tool being held against outward movement in the fork F' by 85 a lug F² arranged on one of the fork members and engaging a recess G² in the cutting tool G, as will be readily understood by reference to Figs. 8 and 9. The rear end of the lever F extends into a longitudinal keyway B⁴ 90 formed in the forward end of the sleeve B, so that when the sleeve B is rotated, the lever F is carried along; and consequently the stock A, to rotate the latter. The back of the lever F is in the form of a cam surface, so that 95 when the sleeve B is pushed lengthwise over the stock A, then a swinging motion is given to the lever F, to swing the cutting edge G' of the cutting tool G outwardly, to engage the wall of the tubular end of the stay bolt I at 100 the inside, with a view to cut the said wall on rotating the stock A and feeding the cutting edge G' outwardly. A spring J held in the slot A' presses against the inner face of the lever F, so as to hold the same in engagement 105 with the keyway B⁴, and one end of the said spring J rests against the stop plate E, and the other end is adapted to abut against

the shoulder A⁵ arranged on the stock A, as plainly shown in Fig. 2.

In order to hold the sleeve B in an outermost position on the stock A previous to rotating the sleeve, a latch K is provided, fulcrumed at K' on the sleeve B (see Fig. 7) and pressed on at its outer end by a spring K² to engage the inner end of the said latch with a recess A⁶ formed transversely in the stock A and adapted to register with the slot B³ formed in the sleeve B and containing the latch K at the time the sleeve B is in an outermost position on the stock A, as illustrated in Fig. 2.

The tool is used as follows: When the sleeve B is in the outermost position on the stock A, as shown in Fig. 2, then the lever F is held in its outermost position by the action of the spring J, so that the cutting edge G' of the cutting tool G is withdrawn within the forward end of the recess A', to permit convenient insertion of the reduced end A² of the stock A into the drill hole I² formed in the stay bolt I. After the end A² is inserted in the drill hole I², then the operator presses the latch K, to disengage the same from the recess A⁶, and then the motor is started, so that its shaft C rotates the sleeve B and the latter, by the lever F engaging the keyway B⁴, is carried along and rotates the stock A. The operator now moves the sleeve B with the motor from the left to the right lengthwise on the stock A, so that the lever F is gradually pressed inward by the action of the sliding sleeve B, so that the cutting edge G' moves outward and in engagement with the wall of the tubular end of the stay bolt I, to cut an annular groove into the said wall. As the sliding movement of the sleeve B is continued, a gradual outward feeding of the cutting edge G' into the

said wall is continued, to finally cut the stay bolt in two a distance inside of the boiler-sheet I'. When this has been done, the motor is stopped and the sleeve G with the motor 45 is caused to slide back on the stock A to its former position, and in doing so the lever F is caused to swing outward by the action of the spring J, so that the cutting edge G' of the cutter G is withdrawn into the slot A'. The tool can now be readily pulled out of engagement with the cut-off outer end of the stay bolt and re-arranged with the drill hole of another stay bolt to repeat the above-described operation. 50

The cutting machine described, while primarily intended for cutting stay bolts after the same have been provided with drill holes I², as above mentioned, may also be used for other purposes; for instance, for 60 cutting boiler flues inside of the boiler head.

Having thus described my invention, I claim as new and desire to secure by Letters Patent:—

A cutting machine for cutting off stay 65 bolts and the like, comprising a stock, a lever extending lengthwise in the stock and carrying a lateral cutting tool, a sleeve slidably mounted on the stock and engaging the lever to feed the cutting tool, said sleeve 70 having a longitudinal groove for receiving the lever whereby to lock the stock and the sleeve, and a latch pivoted to the sleeve and engaging the stock for maintaining the sleeve in its outward position. 75

In testimony whereof I have signed my name to this specification in the presence of two subscribing witnesses.

EARL T. STRONG.
